CLAIM

The ornamental design for an electrical circuit breaker, as shown and described.

DESCRIPTION

FIG. 1 is a front, right and top perspective view of an electrical circuit breaker showing our new design;

FIG. 2 is a right elevation view thereof;

FIG. 3 is a left elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines in the figure drawings are included for the purpose of illustrating unclaimed environment and form no part of the claimed design.
